UNITED STATES PATENT OFFICE

FRANK BOWLEY MITCHELL, OF HOVE, ENGLAND

SOUND-REPRODUCING MACHINE

Application filed July 17, 1923, Serial No. 652,154, and in Great Britain July 20, 1922.

This invention relates to sound-reproducing machines with particular reference to the stylus or primary sound-reproducing agent employed in connection with such machines.

5 Hitherto it has been usual to form the stylus as a hard tapered needle which requires constant renewal as it is practically rendered unfitted for use after playing through one or a relatively small number of records.

10 The object of the present invention is to devise an improved form of stylus wherein this disadvantage will be completely obviated, since a machine constructed and arranged in accordance with my invention will be capable of playing through a very large number of records without requiring any alteration or renewal of stylus.

15 With this and other objects in view, the invention consists in the various details and 20 combinations of parts hereinafter described and more particularly pointed out in the appendant claims.

The accompanying drawings illustrate several modes of carrying out the invention:—

25 Figures 1 and 2 are front elevations showing one convenient form of reproducer in accordance with my invention with the parts shown in different positions;

30 Figures 3 and 4 are front views illustrating certain of the parts shown in Figures 1 and 2 in different positions;

Figure 5 is a sectional view showing the stylus holder of Figures 1 and 2, and

35 Figure 6 is a front view showing the component parts of the stylus holder in Figure 5.

Figure 7 illustrates a perspective view of the stylus holder;

40 Figure 8' is an elevation showing a portion of a modified form of reproducer in accordance with the invention;

Figures 8, 9, and 10 show a still further modification with the parts in various positions;

45 Fig. 11 is a sectional view of a modified form of stylus holder.

Figure 12 is a side elevation of a further modification of apparatus in accordance with the invention;

50 Figure 13 is a perspective view showing a modification similar to Figure 12;

Figure 14 is a view of a still further modification;

Figures 15 and 16 are side views of the modification of Figure 14,

Figures 17 and 18 are views illustrating details, and

Figure 19 is a view illustrating the lower end of the lever *a*.

In carrying my invention into effect in one convenient manner and as illustrated, for example, in Figures 1 to 6, I form my improved reproducer with a groove in one part of its periphery in which is arranged a bent lever *a* pivoted in some convenient position as at *b* and normally retained in its outer position (as shown in Figure 1) by means of a suitable spring, such as *c*. The reproducer is fitted with the usual stylus bar *d* to which is secured, (as, for example, by a screw *e*) a holder (indicated generally by the reference *f* in Figures 1 and 2 but hereinafter described in greater detail) through which is passed a fine wire *g* of a gauge equal approximately to the width of a groove in the sound record so that such wire may serve as the stylus for the machine and being of approximately the same diameter or gauge as the width of a sound groove may be continuously used for the playing of records until the whole of the wire provided has been worn away, so that in this manner I am able on the one machine, without renewal or alteration of the stylus, to play through a very large number of records.

As the wire is of relatively fine gauge it will, in general, require to be gripped close to the operating point in order to give it the necessary stiffness to enable it to operate as a stylus and in conjunction, therefore, with my improved apparatus I prefer to provide means by which the wire may be so gripped, but in a releasable manner, so that when the portion of the wire protruding from its holder is worn away the gripping means may be released to allow a further portion of wire to be protruded, and I further prefer to provide a gauge stop of suitable form in order to limit the amount of the wire so protruded. Such gripping means and gauge stop may be actuated by hand or may be actuated automatically by the operation of removing the

reproducer from a record and allowing the same to rest upon a suitable support or a combination of these methods may be adopted or any other convenient means may be employed for the same purpose.

5 In the form illustrated in Figures 1 to 6 the gauge stop and wire releasing means are adapted to be actuated by hand pressure, for which purpose the bent lever *a* above referred to is adapted to cooperate with a lever or like member *h* having a hook end or extension *h'* adapted to engage a lug or projection upon a lever *i* pivoted by means of a slot *i'* about a pin *i''* and bent at its end *i'''* so as to form a stop for the wire *g*. The lever *i* is normally kept in the position shown in Figure 2 (that is, out of the path of the wire) by means of a bent spring *k* and the wire gripping means to be presently described is operated by the lever *l*.

10 In the form shown in Figures 5 and 6 the wire gripping means comprises a V- or channel-shaped member *l'* adapted to receive a wedge-piece *l''* which is pivoted at *l''* to the lever *l*, the latter being also pivoted at *l'* to the channel-member *l'*. A spring or other means (not shown) may be provided to maintain the lever *l* in the normal position in which the wedge is inserted into the channel member for the purpose of gripping the wire.

15 The arrangement is such that hand pressure on the circumference of the reproducer casing causes an inward movement of the lower end of the lever *a* (which is normally in the position shown in Figure 2) into the position shown in Figure 3 so that it operates the lever *h* to move the stop lever *i* into the position in which the stop portion *i''* comes into the path of the wire, a suitable 20 stop (not shown) being provided to prevent further movement of the gauge member *i*. Further inward movement of the lever *a* does not alter the position of the gauge member *i* but the end of the lever *a* presses upon the 25 upper part of the lever *l*, thus withdrawing the wedge from within the channel and allowing the wire to drop into contact with the gauge stop. On releasing the reproducer the 30 wire is again gripped and the gauge stop is moved out of the way so that the apparatus is ready for re-use.

If necessary or desirable, the upper part 35 of the wire *g* may be formed with a reinforcing or strengthening head *g'*.

Figure 11 shows a modified form of wire grip but having a flat member *m* to grip the wire instead of the wedge shown in Figure 6. In this case the V of the holder is so small 40 that the wire partially protrudes therefrom and in order to prevent point contact with the wire, which might tend to bend the same, I provide a small spring *m'* between the wire and the gripping or holding device.

45 It is obvious that the lifting of the tone

arm may be made to operate the parts in place of the hand pressure above referred to, and one arrangement by which this may be effected is shown in Figures 8 to 10. In this case the reproducer is provided with an extension plate *a'* to which is secured at one end a spring *a''* while the other end carries a pin or pivot-like part *a'''* adapted to engage in a recess in the gauge or stop lever *i*, the latter being also provided with a second recess in which engages a pin *a''''* carried by a spring *a'''* which is somewhat stronger than the spring *a''* and which is secured to a lever *a''''* pivoted to the plate *a'* about the centre *a''''* and carrying a pin *a''''''*.

50 The arrangement is such that upon pressing the lever *a''''* upwards (either by hand or by allowing the reproducer to press downwards upon a support) the pin *a'''* causes the gauge lever *i* to move into the position shown in Figure 10 (that is, into the path of the wire whose position is indicated by the dot and dash line *d'*). Further upward movement of the lever *a* cannot rotate the member *i* any further owing to its engagement with the spring *a''* and consequently any such further upward movement causes the gauge member *i* to be moved upwards, as shown in Figure 10, in which position it is arrested to gauge the amount of wire to be protruded when the wire-gripping device is released. Still further upward movement of the lever *a''''* causes the pin *a''''''* to move the grip-releasing lever *l* so that the wire is allowed to move outwards into contact with the gauge and on releasing the pressure on the lever *a''''* the wire is gripped in this position by the mechanism controlled by lever *l* and then the gauge *i* moved back to the normal position shown in Figure 8.

55 Figure 8' shows a simple hand-operated arrangement in which the wire *g* is held in the holder *f* by the grip of the lever *l*, and the gauge stop in this construction takes the form of a lever *i'* having a quadrant *i''* thereon adapted to be actuated by a rack *i'''* on the end of a spring-controlled lever *i''''*. On pressing this lever inwards towards the reproducer the gauge stop *i'* is rotated into the path of the wire *g*, while further movement of the lever causes the projection *i''''* thereon to move into contact with the lever *l*, thus releasing the wire to contact with the gauge stop, in a manner as previously described, release of the pressure on the lever *i''''* causing the wire to be gripped in its gauged position and the gauge stop to be returned to the normal position shown in the figure.

60 For machines when the reproducer is arranged to work under the record, the form shown in Figure 8' is very suitable, as when the reproducer is moved beyond the record after use the lever *i''''* may meet a cam-shaped extension mounted on the framework (in a similar manner to that hereinafter described

in connection with Figures 12 and 13) and as it passes further out the cam will push the lever in to adjust the stylus as described. Bringing the reproducer back for start will again lock the stylus or, if another form is used, the wire may be pulled up by a permanent magnet.

Figure 13 shows a modification which is somewhat similar to those hereinbefore described but in which the release of the wire is effected by the removing of the reproducer from a record and allowing the same to rest upon a support. The dotted lines show the paths through which the lower part of the holder and the outer side of the tone arm are moving. In this form the reproducer n is provided with a holder f having the wire g gripped therein by means actuated by the lever l and outside the record n' I arrange a rest n^2 for the reproducer, the parts being brought to their correct position by contact of the tone arm n^3 with the stop pin n^4 . When the reproducer is thus positioned on the part n^2 the member o' carried by the spring o^2 which is attached by a screw (not shown) to the back of n^2 acts as the gauge stop and the wire g is released for movement into contact with the gauge stop by the edge n^5 of the member n^2 moving the grip-releasing lever l . Figure 12 shows a modification of the arrangement shown in Figure 13 in which instead of the flat spring o^2 for supporting the gauge stop o' the latter is supported by means of a helical spring o^3 , while the extent of the gauging may be adjusted by means of the stud or set-screw o^4 . The gauge stop o' may be suitably attached to n^2 by a dovetail fitting o^5 .

In each case the object of the spring (o^2 in Figure 13 and o^3 in Figure 12) is to maintain the gauge in action until after the gripping of the wire has been effected by the removal of the reproducer from the rest, the lever l after such removal being returned to its normal or gripping position by means of a suitable spring mounted behind on its spindle i^6 . A modified form of reproducer is shown in Figures 14 to 18 where the operation of renewing the working point of the stylus is caused by rotary movement of the reproducer about the centre of the diaphragm. In this modification the reproducer can rotate upon the tone arm to which it is suitably attached in any well known manner. The tone arm carries a fixed rack p and lug p' a front view of which is shown in Figure 17 and an end view in Figure 15. The rack and stop are omitted from Figure 16 in order to avoid confusion. In addition to the wire-gripping device f which, by means of a projection f' is held by screw e in the ordinary needle holder, and which is actuated by lever l , the reproducer also carries a pinion p^3 which coacts with the fixed rack p . When the reproducer is rotated with the center of the diaphragm as

centre of rotation, the pinion p^3 moves along rack p and is itself rotated, thus causing movement of gauge stop p^2 , to which it is attached, into position in the path of the wire. The movement of the end of p^2 is shown by 70 the chain-dotted arc in Figure 14. The lug p' then contacts with the end of lever l as shown in Figure 15 and upon further movement moves it to release the wire which, as before, falls on to the gauge p^2 . Backward 75 rotation of the reproducer first moves p' out of contact with l which returns under spring control to cause the wire to be again gripped. The gauge p^2 is then moved to its normal position by means of pinion p^3 and rack p , 80 and the reproducer is again ready for use.

It will be understood that the means adopted for holding the wire and the arrangements provided for gauging the amount of wire to be protruded when a part of the wire has 85 been worn away, as also the means adopted for operating the wire-gripping and gauging parts, may be variously modified according to the kind of machine to which the invention is to be applied or any practical requirements 90 that may have to be fulfilled.

Further, in all cases where necessary or desirable the wire g (Fig. 1) may be associated with a spring member g' adapted to press the wire outwards against the gauge when 95 the grip is released and such spring may act upon a cup or like member g^2 to facilitate the proper positioning of the wire when the holder is inserted in place in the reproducer.

Having now described my invention, what 100 I claim as new and desire to secure by Letters Patent is:—

1. In a sound reproducing machine the combination of a sound-box, a stylus formed of fine wire, a stylus bar for supporting said stylus, means for gripping said stylus near its operative end and a movable lever mounted upon said sound-box independent of said stylus bar for operating and releasing said gripper means.

2. In a sound reproducing machine the combination of a sound-box, a stylus formed of fine wire, a stylus bar for supporting said stylus, spring actuated means for gripping said stylus near its operative end and a movable lever mounted upon said sound-box independent of said stylus bar for operating and releasing said gripping means.

3. In a sound reproducing machine the combination of a sound-box, a stylus formed of fine wire, a stylus bar supporting said stylus, means for feeding the stylus endwise, means for gripping said stylus near its operative end and a movable lever mounted upon said sound-box independent of said stylus bar for operating and releasing said gripping means.

4. In a sound reproducing machine the combination of a sound-box, a stylus formed of fine wire, a stylus bar supporting said

stylus, means for gripping said stylus near its operative end, means for feeding the stylus endwise, means carried on the sound-box independent of said stylus bar for limiting the extent of such feed and a movable lever mounted upon said sound-box independent of said stylus bar for operating and releasing said gripping means.

5. In a sound reproducing machine the combination of a sound-box, a stylus formed of fine wire, a stylus bar supporting said stylus, means for gripping said stylus near its operative end, spring means carried upon said sound-box independent of said stylus bar for feeding the wire endwise, means carried upon the sound-box independent of said stylus bar for limiting the extent of such feed and a movable lever mounted upon said sound-box independent of said stylus bar for 10 operating and releasing said gripping means.

6. In a sound-reproducing machine the combination of a sound-box, a stylus formed of fine wire, a holder for said stylus, means for gripping said stylus near its operative end in said holder, means carried by the sound-box for feeding said stylus wire endwise, a gauge stop also carried upon said sound-box for limiting the extent to which said stylus may be protruded from said holder, and a movable lever mounted upon said sound-box independent of said stylus holder for moving said gauge stop into or out of its operative position and for operating and releasing said gripping means.

35. 7. In a sound reproducing machine the combination of a sound-box, a stylus formed of fine wire, a holder for said stylus, means for gripping said stylus in said holder, a movable gauge stop mounted upon said sound-box independent of said holder for limiting the extent to which said stylus may be protruded from said holder and means also carried by said sound-box for operating both the gripping means and the gauge stop.

45. 8. In a sound-reproducing machine the combination of a sound-box, a stylus formed of fine wire, a holder for said stylus, spring means for gripping said stylus near its operative end in said holder, a movable gauge stop mounted upon said sound-box independent of said holder for limiting the extent to which said stylus may be protruded from said holder, and means also carried by said sound-box for operating by one movement both the 55 gripping means and the gauge stop.

9. In a sound-reproducing machine the combination of a sound-box, a stylus formed of fine wire, a holder for said stylus, means for feeding said stylus endwise, means for 60 gripping said stylus near its operative end in said holder, a movable gauge stop mounted upon said sound-box independent of said holder for limiting the extent of feed of said stylus and a lever carried on said sound-box 65 independently of said holder, said lever oper-

ating first to move the gauge stop into gauging position, second, to release the stylus gripping means to allow the stylus wire to be fed up to said gauge stop, third, to re-grip the stylus in said holder and finally to 70 replace the gauge stop in its normal inoperative position.

10. In a sound-reproducing machine the combination of a sound-box, a stylus formed of fine wire, a stylus bar for supporting said stylus, means for gripping said stylus near its operative end, a movable lever mounted upon said sound-box independent of said stylus bar for operating and releasing said gripping means and a movable gauge stop 75 also mounted upon said sound-box with arrangements to move same under the stylus point for adjustment of the stylus and then out of the way when the stylus is in operation on the record.

11. In a sound-reproducing machine the combination of a sound-box, a stylus formed of fine wire, a holder for said stylus, means for feeding said stylus endwise, spring means for gripping said stylus near its operative 90 end in said holder, a movable gauge stop mounted upon said sound-box independent of said holder for limiting the extent of feed of said stylus and a lever mounted upon said sound-box independent of said stylus holder, 95 said lever operating first to move the gauge stop into gauging position, second, to release said stylus gripping means to allow the stylus wire to be fed up to said stop, third, to re-grip the holder in said stylus and finally to 100 replace the gauge in its normal inoperative position.

12. Apparatus according to claim 5 in combination with a rest upon said machine adapted to support the sound box, and coacting means upon said rest adapted to move the movable lever when the sound box is placed upon the rest.

In testimony whereof I have signed my name to this specification.

FRANK BOWLEY MITCHELL.
